THERMOSTATIC GAS VALVE

Filed Feb. 3, 1932

UNITED STATES PATENT OFFICE

2,023,640

THERMOSTATIC GAS VALVE

Clarence H. Morrow, Cleveland, Ohio, assignor to
 The Hotstream Heater Company, Cleveland,
 Ohio, a corporation of Ohio

Application February 3, 1932, Serial No. 590,572

4 Claims. (Cl. 158—117.1)

This invention relates to thermally controlled valves such as are used for water heaters or the like, and more particularly to a pilot controlled valve, its object being to provide a new and improved arrangement of the parts of a device of this character, adapting it to utilize a poppet type valve and simple operating and trigger control mechanism, and in which the gas supply for the pilot valve may be taken from the main line, ahead 5 of the valve, and is supplied to the pilot burner through the thermostatic control elements.

A further object of the invention is to provide a valve of this kind in which the thermostatic elements and poppet valve are axially aligned with each other, to the end of simplifying and cheapening the construction, and wherein the manually operable control parts of the trigger mechanism are movable transversely to said axis and are easily accessible.

Further objects of the invention are in part obvious and in part will appear more in detail hereinafter.

In the drawing Fig. 1 is a longitudinal sectional elevation through one form of valve mechanism embodying the invention; Fig. 2 is a sectional view on the line 2—2, Fig. 1; Fig. 3 is a view corresponding to Fig. 1, said view being partly in section and showing another position of the parts; Fig. 4 is an end view from the left in Fig. 1; and Fig. 5 is a perspective view of the end burner member, Fig. 1.

The valve mechanism shown in the drawing comprises a hollow casing or body 1 provided with a cross wall 2 having a through opening 3 providing communication between the supply and discharge chambers 4, 5 which are adapted in the usual manner for connection to the supply pipe 6 and discharge pipe 7. Flow of gas through the valve is controlled by a poppet type valve member 8, the stem of which is guided in an opening of a boss 9 on a cap 10 threaded to the casing, said valve being normally pressed toward its seat by a compression spring 8'. The valve is moved to open position by manually operable means, such as the rod 11 guided at one end in an opening of a boss 12 of the casing and sliding transversely across the axis of the valve stem and near its opposite end having a shoulder 13 forming an abutment to receive one end of a leaf spring 14, which at its other end enters a recess of the casing and abuts a shoulder 15 thereof. Fig. 1 shows the valve closed. By pressing with the finger upon the exposed end of the rod, it may be moved downwardly in Fig. 1 to the position shown in Fig. 3, thereby flexing, bowing or buckling the spring 14

to the position shown in Fig. 3, and applying pressure to the valve to open the same. The outer or finger end of the rod 11 is guided in a plug 16 threaded into the casing, and to normally conceal the rod and prevent gas escape, its outer end is covered by a cap 17 also threaded to the casing. This cap is removed when it is desired to manually operate the mechanism.

For the purpose of holding or maintaining the valve in open position, latch or trigger mechanism is provided, including thermally controlled parts governed by operation of a pilot burner and effective upon the operating rod 11. In the arrangement shown the valve casing is provided with a threaded extension 18 into which is screwed 10 one end of a tubular member 19, made of steel or some relatively non-expansive material, and held firmly in any position to which it may be adjusted by a lock nut 20. The outer end of said tube is provided with a plug 21 into which is 20 threaded the outer end of a relatively expansible thermal element 22, which, for example, may be a copper or brass rod, the inner end of which carries an extended pin 23 sliding freely in an opening of a plug 24, its inner end lying close to a latch 25 member 25 attached to the rod 11.

Tube 19 not only serves as one of the thermostatic elements, but also as a support for the pilot burner, which includes a hollow body portion 26' 30 threaded upon the outer projecting end of the rod 22 and having a mixing chamber 26 therein provided with ports 27 open to atmosphere. The outer end of the rod 22 is also provided with a channel 28 which provides communication between the chamber 29 inside of the tube 19 and 35 the mixing chamber 26, said chamber 29 being provided with suitable means for supplying gas thereto, such as the passage 30 leading to a supply pipe 31 which may be connected to any gas supply, such as to a portion of the supply line ahead 40 of the valve. The outer end of the burner member is provided with suitable burner parts, which, in the present instance, are of a form providing proper pilot gas flame regardless of the position to which the tube 19 may be adjusted by its 45 rotating adjustment. The burner in this instance is formed of a plug 32 having a round head 33, while its shank is more or less star shaped in cross section, as shown in Fig. 5, providing a series of circumferentially distributed channels 34. 50 This plug is a press fit in the end of the burner tube and may be more or less driven into the same to various positions to control the size of the burner openings.

Fig. 3 shows the operative position of the parts. 55

It is assumed in that view that the supply to the pilot burner through the pipe 31 has been turned on and that the pilot flame is lighted. No matter what is the position of adjustment of the tube 19 some gaseous mixture flows out from the mixing chamber through the upper burner orifices around the star shaped shank 32, so that the pilot flame burns easily without sooting and without tendency to clog the burner openings, as is the case when the openings happen to be in the bottom only of the pilot burner tube. The heat of the pilot flame more or less heats all adjacent or contiguous metal parts, thereby expanding rod 22 so that the inner end of its extension 23 projects out beyond the end of the latch 25, thereby holding the parts in the position shown in Fig. 3, with the valve 8 open so long as the pilot continues to burn.

Should the pilot flame go out for any reason, the parts cool and the rod 22 contracts, moving the end of its extension to the position shown in Fig. 1 and thereby releasing the rod 11 to the stored expansive power of the spring 14, which immediately straightens out and permits the valve 8 to be moved to the closed position by its spring 8'. The connection between spring 14 and valve 8 may be more or less self accommodating, such as by the provision of a ball 35 having a small seat 36 passing through an opening in the spring, said ball lying in a socket of the valve and more or less accommodating itself to the valve in its to and fro movements.

When the valve has been closed by the pilot flame going out, as described, it cannot be opened except by manual operation, necessitating removal of the cap 17, downward pressure upon the end of the rod 11, and ignition of the pilot burner. The rod 11 is held depressed with the finger until the heat of the pilot burner sufficiently expands rod 22 to again latch the parts in the manner shown in Fig. 3, when the cap is reapplied and the parts operate as before.

With this arrangement, the supply of gas to the pilot burner is independent of the valve itself and is not cut off by closing of the valve, but these pilot burners require only a small amount of gas, which in any event is wasted to the stack and does not escape into the open room. Moreover, the thermostatic elements themselves form the gas supply to the burner and the valve is of the poppet type and in alignment with the thermostatic elements, so that the device is more or less symmetrical and relatively low in cost of construction. At the same time the manually operated parts move transversely and provide an arrangement in which access may be had interchangeably either to the valve or to the operating rod by the two removable caps 10 and 17.

Of course, it will be readily understood that the valve mechanism described is capable of some setting or adjustment of the parts and particularly of the burner tube 19, which is rotatably and longitudinally adjustable in the casing. By screwing this tube in or out and fixing it in the desired position of adjustment by the lock nut 20, the inner end of the extension 23 may be positioned for proper cooperation with the latch 25. This adjustment not only takes care of temperature differences due to surrounding atmospheric conditions or other causes, but, more important, is an adjustment to take account of inaccuracies or differences in the lengths of the parts or adjustments thereof, such as at the threaded connections between the extension 23 and the rod 22 or between the rod 22 and the plug

21. After the parts are all assembled the tube 19 is adjusted while cold or at normal atmospheric conditions to such position that the trigger 25 can just pass by the end of the extension 23. Consequently, when the parts are heated up by the pilot flame proper latching is assured.

Under certain conditions the device need not function as a pilot burner, but only as a thermostat. For example, the valve mechanism may control the flow of gas to a burner, not shown, the flame of which is directed upon or in some manner heats the thermostatic elements shown in the drawing, causing the copper member to expand and produce the latching effect described. When the flame goes out the thermostatic elements cool and release the valve for its closing operation. With this arrangement, the burner shown in Fig. 1, including the base 26', the hollow body and the end member 32, may be entirely omitted, the flames of the burner not shown playing directly upon, or heating the outer thermostatic element, or the burner shown in Fig. 1, including the same parts, may be replaced by a cap of solid imperforate metal threaded upon the exposed end of the rod 22 in the same manner as base 26'. This may be a solid metal mass that conducts the heat to the thermostatic elements. In either case, the supply connection 30 for the pilot burner is either left open or capped, because no gas flows through it.

Moreover, valve 8 need not necessarily be a poppet valve, but may be any kind of valve movable generally in the same direction as the length of the thermostatic elements, or, in other words, transversely to the direction of motion of rod 11.

Other advantages of the construction will be apparent to those skilled in the art.

What I claim is:

1. Valve mechanism, comprising a hollow casing having supply and discharge chambers inter-
communication of which is established by a port therebetween, a valve controlling inter-communication of said chambers, means normally urging said valve to move to closing position relative to said port, a manually operable member slidably mounted in said casing and provided with an abutment, a leaf spring arranged within said casing between said member and said valve and having one of its ends engaging the abutment of said slideable member and the other of its ends engaging a fixed abutment with which said casing is provided, and ball and socket connecting means operatively connecting an intermediate portion of said spring to said valve, the parts being so constructed and arranged that manual movement of said slideable member toward said fixed abutment causes said spring to flex or bend so that its intermediate portion moves transversely of said member and moves said valve to open position relative to said port.

2. Valve mechanism, comprising a hollow casing having supply and discharge chambers inter-communication of which is established by a port therebetween, a valve arranged in one of said chambers for cooperation with said port to control inter-communication of said chambers, means normally urging said valve to move to closing position relative to said port, a manually operable member slidably mounted in the other of said chambers and provided with an abutment, and a leaf spring arranged within said last named chamber and having its intermediate portion operatively related with said valve through said port, said spring having one of its ends engaging the abutment of said slideable member and hav-

ing its other end engaging a fixed abutment with which said casing is provided, the parts being so constructed and arranged that manual movement of said slideable member toward said fixed abutment causes said spring to flex or bend so that its intermediate portion moves transversely of said member through said port and moves said valve to open position relative to said port.

3. Valve mechanism, comprising a casing having a gas inlet and a gas outlet inter-communication of which is effected by a port therebetween, a spring-pressed valve cooperating with said port for controlling such inter-communication, a rod slidably mounted in said casing, an abutment on said rod, an abutment on said casing, a leaf spring arranged within said casing and having one of its ends abutting said rod abutment and the other of its ends abutting said casing abutment, means operatively connecting an intermediate portion of said spring with said valve, whereby slideable movement of said rod effects movement of said valve relative to said port, and thermostatically controlled means adapted to be operatively connected with said rod for releasably maintaining said rod, when the thermostat of said last named means is in a heated condition, in such position that said spring releasably

maintains said valve in open position relative to said port.

4. Valve mechanism, comprising a casing having a gas inlet and a gas outlet inter-communication of which is effected by a port therebetween, a spring-pressed valve cooperating with said port for controlling such inter-communication, a rod slidably mounted in said casing, an abutment on said rod, an abutment on said casing, a leaf spring arranged within said casing and having one of its ends abutting said rod abutment and the other of its ends abutting said casing abutment, means operatively connecting an intermediate portion of said spring with said valve, whereby slideable movement of said rod effects movement of said valve relative to said port, and thermostatically controlled means for releasably maintaining said rod, when the thermostat of said last named means is in heated condition, in such position that said spring releasably maintains said valve in open position relative to said port, said thermostatically controlled means including a projection on said rod and a thermostatic element arranged in alignment with said valve and said port and adapted to be releasably associated in abutting relation with said rod projection.
